UNITED STATES PATENT OFFICE.

HARRY E. RUCKERT, OF PHILADELPHIA, PENNSYLVANIA, ASSIGNOR TO AMERICAN STAMPING MACHINE CORPORATION, OF PHILADELPHIA, PENNSYLVANIA, A CORPORATION OF DELAWARE.

DESIGN FOR A PLATE OR SIMILAR ARTICLE.

Application filed November 25, 1924. Serial No. 11,474. Term of patent 14 years.

To all whom it may concern:

Be it known that I, HARRY E. RUCKERT, a citizen of the United States, residing at Philadelphia, in the county of Philadelphia and State of Pennsylvania, have invented a new, original, and ornamental Design for a Plate or Similar Article, of which the following is a specification, reference being had to the accompanying drawings, forming a part thereof.

In the drawings, Fig. 1 is a top plan view and

Fig. 2 is a side elevation of a plate embodying the design.

What I claim is—

The ornamental design for a plate or similar article, substantially as shown.

HARRY E. RUCKERT.
